PNEUMATIC WINDOW OPERATING DEVICE

Mario Dineo, Melvindale, Ernest Komjathy, Detroit, and Charles S. Komjathy, Inkster, Mich.

Application August 9, 1937, Serial No. 158,204

1 Claim. (Cl. 268—125)

This invention relates to window operating devices, and its general object is to provide a pneumatic device of that character which is primarily designed for use with passenger vehicles, for individually operating the window thereof to closed and opened positions, and such can be accomplished by our device, merely by actuating valve means that is controlled by handled means conveniently arranged with respect to its window.

10 A further object is to provide a pneumatic device that is capable of being operated in an efficient manner, with a minimum amount of compressed air, from a suitable source of supply, such as for instance from a pump operated by the 15 motor of the vehicle.

Another object is to provide a pneumatic window operating device that is simple in construction, easy to install, inexpensive to manufacture, and extremely efficient in operation, use and 20 service.

This invention also consists in certain other features of construction and in the combination and arrangement of the several parts, to be hereinafter fully described, illustrated in the accompanying drawing and specifically pointed out in 25 the appended claim.

In describing the invention in detail, reference will be had to the accompanying drawing wherein like characters denote like or corresponding parts 30 throughout the several views, and in which:

Figure 1 is a fragmentary view illustrating our device in use, with the parts arranged in full lines when in a position with the window open, and in dotted lines, with the window closed.

35 Figure 2 is a sectional view taken approximately on line 2—2 of Figure 1, looking in the direction of the arrows.

Figure 3 is a sectional view taken approximately on line 3—3 of Figure 1, looking in the direction 40 of the arrows.

Referring to the drawing in detail, the reference numeral 1 may indicate a door provided at its upper portion with a window opening, adapted to be closed by a sliding glass panel 2 mounted 45 for movement in guideways 3 and limited in its downward movement by stops 4.

Fixed within the lower portion of the door 1 is a cylinder 5 that has mounted for slidable movement therein a plunger in the form of a piston 6 of a length to extend above the cylinder, and the lower end of the piston is provided with 50 grooves having rings 7 mounted therein, that act as packing means, as will be apparent.

The upper end of the piston 6 is recessed to 55 provide a reduced portion 8 and mounted in the

recess, as well as fixed to the reduced portion by securing means such as bolt and nut connections 9 is the intermediate portion of a block 10 which is provided with reduced end portions 11, the latter having secured thereto by bolt and nut connections 12, the lower ends of arms 13 that rise therefrom in diverging relation with respect to each other, as clearly shown in Figure 1. The upper ends of the arms 13 have resting thereon the lower edge of the panel 2 which is secured to 10 ears 14 that are formed on and rise from the arms and securing means are shown as being bolt and nut connections 15.

From the foregoing, it will be seen that the piston is connected to the panel 2 through the 15 instrumentality of the block and arms 13 so that upon movement of the piston the panel will be raised and lowered to closed and opened positions.

The piston is moved upwardly by compressed 20 air, and for that purpose, air is introduced in the bottom of the cylinder which is closed by a cap 16 threaded thereto, and the cap has an opening therein within which extends one end of a pipe line 17, the opposite end being secured 25 to the body of a three-way valve 18, that includes a core rotatably mounted therein, with passage-ways movable for registration with a bleed port 19, an inlet port 20, and a port 21 for the pipe line 17. The port 20 has a pipe line 22 connected 30 thereto and which leads to a suitable source of air under pressure or to an air pump which may be operated by the motor of the vehicle, and the pipe line 22 has a check valve 23 therein, for a purpose which will be presently described.

35 The valve is actuated by a lever 24 that is secured to the core, and the lever is provided with a slot 25 longitudinally arranged therein for slidably receiving a pin 26 that is secured to and extends laterally from an upright lever 27 which 40 is suitably guided and has a knob 28 secured to the upper end thereof, providing a handle.

From the above description and disclosure of the drawing, it will be obvious that we have provided a pneumatic window operating device for 45 motor vehicles, and in the use thereof, the valve is moved to the dotted line position to allow the compressed air to pass from the pipe line 22, through the valve and pipe line 17, to act upon the lower end of the piston 6, thereby resulting 50 in the panel 2 being arranged to closed position, as shown in dotted lines. When it is desired to lower the window, the valve is moved to the full line position which will allow the air to escape 55 through the bleed port, and the panel will drop

by gravity due to the weight thereof, together with the arms, block and piston. The panel is not only raised by compressed air, but is held in raised position by the air being trapped in the cylinder, pipe line 17, valve 18 and that portion of the pipe line 22 between the valve 18 and check valve 23.

It is thought from the foregoing description that the advantages and novel features of the invention will be readily apparent.

It is to be understood that changes may be made in the construction and in the combination and arrangement of the several parts, provided that such changes fall within the scope of the appended claim.

What we claim is:

A pneumatic device for raising and lowering a slidably mounted transparent closure panel of a vehicle window, and comprising a cylinder, a pis-

ton slidably mounted in said cylinder and having a reduced upper end extending through the cylinder, a block secured to the reduced upper end and having reduced opposite ends, arms secured to the reduced opposite ends of the block and diverging therefrom, ears formed on the outer ends of the arms and fixed to the panel with the latter resting upon the arms, means for conveying compressed air to the cylinder below the piston, and means for controlling the passage of air through the conveying means to introduce air in the cylinder to raise and hold the panel in raised position, and to exhaust the air from the cylinder to allow the panel to lower by the action of gravity.
